UNITED STATES PATENT OFFICE.

WILLIAM B. COGGER, OF GRAND RAPIDS, MICHIGAN, ASSIGNOR TO AMERICAN SEATING COMPANY, OF CHICAGO, ILLINOIS, A CORPORATION OF NEW JERSEY.

DESIGN FOR A SCHOOL-DESK STANDARD.

No. 40,044.

Specification for Design.

Patented June 8, 1909.

Application filed June 29, 1908. Serial No. 441,038. Term of patent 7 years.

To all whom it may concern:

Be it known that I, WILLIAM B. COGGER, a citizen of the United States, and a resident of Grand Rapids, in the county of Kent and State of Michigan, have invented a new, original, and ornamental Design for a School-Desk Standard, of which the following is a specification, reference being had to the accompanying drawing, forming part thereof.

The figure is a side view of a school desk standard showing my design.

I claim—

The ornamental design for a school desk standard, as shown.

WILLIAM B. COGGER.
